(57) **CLAIM**

The ornamental design for a packable, wearable medical blanket that folds into a storage pouch, as shown and described.

DESCRIPTION

FIG. 1 is a front elevation view of the packable, wearable medical blanket that folds into a storage pouch shown in a configuration of use shown folded into a storage pouch;

FIG. 2 is a back elevation view thereof;
FIG. 3 is a left elevation view thereof;
FIG. 4 is a right elevation view thereof;
FIG. 5 is a right front perspective view thereof;
FIG. 6 is a left back perspective view thereof;
FIG. 7 is a top plan view thereof;
FIG. 8 is a bottom plan view thereof;
FIG. 9 is a 3/4 front right perspective view of the storage pouch, with the flange opening facing to the back with the packable, wearable medical blanket folded inside and secured by the carabiner latch to the storage pouch thereof;
FIG. 10 is a 3/4 back left perspective view of the storage pouch, with the flange opening facing to the back with the packable, wearable medical blanket folded inside and secured by the carabiner latch to the storage pouch thereof;
FIG. 11 is the front elevation view of the storage pouch secured to the packable, wearable medical blanket by the carabiner latch thereof;
FIG. 12 is the front elevation view of the storage pouch with the left side of the packable, wearable medical blanket folded horizontally inward toward the center third of itself thereof;
FIG. 13 is the front elevation view of the storage pouch with the right side of the packable, wearable medical blanket folded over the two-thirds column of the blanket at the center thereof;
FIG. 14 is the front elevation view of the storage pouch with the packable, wearable medical blanket folded vertically into thirds. The lower third of the blanket is folded upward toward the center of itself thereof;
FIG. 15 is the front elevation view of the storage pouch with the vertical folded thirds of the packable, wearable medical blanket. The final third of the blanket is folded upward into itself thereof;
FIG. 16 is the front elevation view of the storage pouch with the packable, wearable medical blanket folded and secured within thereof;
FIG. 17 is a top plan view of the storage pouch with the packable, wearable medical blanket folded inside, with the flange closed in a forward closed position with the carabiner latch attached to the left upper corner on the exterior thereof;
FIG. 18 is a top plan view of the storage pouch with the flange folded to the rear of itself with the packable, wearable medical blanket folded within thereof;
FIG. 19 is a bottom plan view of the storage pouch with the packable, wearable medical blanket folded inside with the flange closed with the carabiner latch in view at the left upper corner of the exterior thereof;
FIG. 20 is a front elevation view showing the rolled storage pouch shown through the front surface of the kangaroo pocket affixed to the inside left corner with the carabiner latch thereof;
FIG. 21 a front elevation view showing the rolled and attached storage pouch shown through the front surface of the kangaroo pocket affixed to the inside left corner with the carabiner latch. While showing the packable, wearable medical blanket in a position of use with the arms of the user through the sleeves in a downward position thereof;
FIG. 22 is a 3/4 front perspective left view of the storage pouch with the carabiner latch attached to the left upper corner. The bottom first third of the storage pouch is folded upward to the back thereof;
FIG. 23 is a 3/4 front perspective left view of the storage pouch with the carabiner latch in view at the left lower

corner. The top third of the storage pouch is folded downward, the back lapping over the bottom third of itself thereof;
FIG. 24 is a 3/4 back perspective right view of the folded storage pouch with the top third of the pouch folded over the bottom third of itself, with the carabiner latch attached to the lower right corner thereof;
FIG. 25 is a front elevation view of the packable, wearable medical blanket thereof;
FIG. 26 is a back elevation view of the packable, wearable medical blanket thereof;
FIG. 27 is a 3/4 right front perspective view of the packable, wearable medical blanket thereof; the 3/4 left front perspective view is a mirror image of the 3/4 right front perspective view;
FIG. 28 is a 3/4 right back perspective view of the packable, wearable medical blanket thereof; the 3/4 left front perspective view is a mirror image of the 3/4 right back perspective view;
FIG. 29 is the exterior plan view of the packable, wearable medical blanket, outer front and back full lengths with the cocoon hood, kangaroo pocket and sleeves in view thereof;
FIG. 30 is the exterior plan view of the packable, wearable medical blanket with the front and back full lengths are in view with the kangaroo pocket. The cocoon hood and sleeves are inverted to the interior of the front side thereof;
FIG. 31 is the interior plan view of the packable, wearable medical blanket on the underside, front and back full lengths are in view, cocoon hood and sleeves which are inverted from the exterior front side thereof;
FIG. 32 is the right side elevation view of the packable, wearable medical blanket, the front and back full length with cocoon hood and sleeves thereof; the left side elevation view is a mirror image of the right elevation view;
FIG. 33 is a front interior elevation view of the packable, wearable medical blanket's cocoon hood and neckline on the interior thereof;
FIG. 34 is a back interior elevation view of the packable, wearable medical blanket's cocoon hood thereof;
FIG. 35 is the right exterior elevation view of the packable, wearable medical blanket's cocoon hood, the left side elevation view is a mirror image of the right side elevation view thereof;
FIG. 36 is a front exterior elevation view showing the packable, wearable medical blanket in a position of use as a poncho with the arms extended out;
FIG. 37 is a back exterior elevation view of the packable, wearable medical blanket thereof;
FIG. 38 is a front exterior elevation view showing the packable, wearable medical blanket in a position of use with the arms of the user through the sleeves in a downward position;
FIG. 39 is a back exterior elevation of the packable, wearable medical blanket thereof;
FIG. 40 is a left exterior elevation view of the packable, wearable medical blanket with the arms of the user raised forward; the right elevation view is a mirror image of the left elevation view;
FIG. 41 is a exterior plan view of the packable, wearable medical blanket with the sleeves, seams and cocoon hood in view thereof;
FIG. 42 is a bottom plan view of the packable, wearable medical blanket with the sleeves, sleeve openings, seams and neck opening for the cocoon hood in view thereof;

FIG. 43 is a right perspective view of the packable, wearable medical blanket in a position of use; the left perspective view is a mirror image of the right perspective view; FIG. 44 is a left plan view of the packable, wearable medical blanket in a position of use; the right plan view is a mirror image of the left plan view thereof;

FIG. 45 is a front profile view of the packable, wearable medical blanket shown in a seated position of use thereof; FIG. 46 is a front elevation view of the packable, wearable medical blanket showing the chest area and the upper kangaroo pocket thereof; and,

FIG. 47 is a $\frac{3}{4}$ right perspective view of the packable, wearable medical blanket in a seated position of use; the $\frac{3}{4}$ left perspective view is a mirror image of the $\frac{3}{4}$ right perspective view thereof.

FIGS. 36, 37, 38, 39, 40, 43, 44, 45, 46 and 47 are shown with broken lines of a human figure that represent optional environmental subject matter only and form no part of the claimed design.

FIGS. 43, 44, 45 and 47 are shown with broken lines that represent optional environmental subject matter only and do not form part of the claimed design.
